UNITED STATES PATENT OFFICE.

CHESTER H. BEACH, OF RACINE, WISCONSIN.

ROTARY CLOTH-CUTTER.

1,314,382.

Specification of Letters Patent. Patented Aug. 26, 1919.

Application filed July 31, 1918. Serial No. 247,476.

To all whom it may concern:

Be it known that I, CHESTER H. BEACH, a citizen of the United States, residing at Racine, in the county of Racine and State 5 of Wisconsin, have invented certain new and useful Improvements in Rotary Cloth-Cutters, of which the following is a specification.

My invention relates to improvements in 10 rotary cloth cutters, the present application being filed as a continuation of, and substitute for, my co-pending application filed October 4, 1915, Serial No. 54,061.

The objects of my invention are to provide 15 a very simple and efficient device of this character, and to provide improved means for sharpening the rotary cutting blade.

In the accompanying drawings I have 20 illustrated one embodiment of the invention. Other forms thereof may be devised, however, and, therefore, I do not wish to limit myself to the details of the preferred embodiment herein described.

Figure 1 is a side elevation of the device; and

Fig. 2 is a section on the line 2—2 of Fig. 1.

The motive power is supplied by a small 30 electric motor 1, provided with a suitable handle 2, by means of which the entire structure may be guided in use, and by which it may also be lifted. A push button 3 projects from the handle and controls 35 the motor, the operator merely pressing the button in order to cause the armature to rotate. The end of the motor opposite the handle is provided with a boss 4 through which the armature shaft 5 projects, said 40 shaft being provided with a plurality of pulleys 6 and 7, which are preferably of the ordinary flanged type.

The motor is hinged as at 8 to a rearwardly projecting arm 9 constituting a 45 part of the vertically disposed plate 10, which plate is rigidly secured in any suitable manner to a thin, wide base-plate 11, which supports the entire structure and permits it to be readily slid along the table or 50 other support on which the cutting operation is carried out. The outer margin of the base-plate 11 is brought down to a sharp edge whereby said plate may be readily slid under the cloth, or other material being cut, without danger of catching in it.

Mounted substantially centrally of the

vertical plate 10 is a stud or stub-shaft 12, one end of which carries the rotary cutting blade 13, while on the other end of said shaft is mounted a suitable pulley 14, 60 whereby said cutting blade may be driven by power derived from the armature shaft 5 of the motor by means of a suitable belt 15 which engages said pulley 14 and the outer pulley 7 on the end of said armature 65 shaft. The tension of the belt 15 may be readily adjusted by means of a screw 16, which extends through the outer end of the supporting arm 9 into contact with the underside of the motor, as shown more 70 clearly in Fig. 1 of the drawings. From this it will be readily observed that by turning the screw 16 in or out, the motor and its shaft will be either raised or lowered relatively to the vertical plate 10 and 75 the stub-shaft 12 carried thereby, whereby the tension of the belt 15 may be regulated to secure the most effective driving engagement. It will also be noted that by turning the screw 16 out far enough, the outer 80 end of the motor may be lowered sufficiently to permit of the belt being entirely removed from its pulleys.

The plane of rotation of the rotary cutter is preferably at right angles to the plane 85 of rotation of the driving pulley on the armature shaft, and, accordingly, the belt 15 is preferably twisted as shown to permit this driving to be effected without the use of gearing. The rotary cutter is of thin 90 metal and has a sharp razor-like edge which is protected and guarded by bending over the edge 17 of the supporting plate 10, said plate being of circular outline in order to conform to the shape of the blade. 95

Pivotedly mounted on the boss or hub 4 in any suitable manner, preferably by means of an annular collar such as shown at 18, is an arm or lever 19 which carries a stud 20, the latter supporting a small grinding 100 wheel 21 and a pulley 22 associated therewith in such wise that said wheel may be driven from the inner pulley 6 mounted on the armature shaft by means of a belt 23. The arm or lever 19 may be retained 105 in position on the boss 4 in any suitable manner, it being shown held thereon in the drawings, however, by means of a small ball-shaped member 24, which is normally held by means of a coil spring 25 in engagement with an annular groove 26 which extends around said boss, said spring be- 110

ing contained within a suitable housing 27 carried by the collar 18. It is preferred to provide a spring which will exert sufficient pressure upon the ball 24 to retain the arm 19 in any desired position relative to the boss 4. In order to insure a more positive retention of the arm in its upright position as shown in Fig. 1 of the drawings, however, a depression 26^a may be provided in the top of the boss slightly deeper than the groove 26, whereby when the arm is moved to its upright position the ball 24 will snap into said depression, thereby holding said arm against accidental displacement.

In using the grinding wheel to sharpen the blade, the arm 19 is simply swung to lowermost position, first on one side and then on the other side of the blade, as shown 20 in dotted lines in Fig. 2. The plate 10 is cut away or slotted, as shown at 28, to permit the grinding wheel to be held first against one side and then against the other side of the rotary cutter to grind a fine edge 25 thereon without being interfered with by said plate. It will be seen that the grinding wheel rotates in a plane at right angles to the plane of rotation of the cutter, and therefore is very effective in its action.

30 Whenever the motor is running, the grinding wheel rotates, provided the belt 23 is in position on the pulleys 6 and 22. It is obvious, however, that when the grinding wheel is not being used, rotation thereof is 35 not necessary, and in fact would be objectionable. It is therefore preferred to form the belt 23 of rubber or other suitable elastic material, whereby when the grinding wheel is not in use the said belt may be 40 snapped back over the collar 18 of the arm 19, as shown in dotted lines in Fig. 1, thereby rendering the said wheel inoperative. The tension of the belt 23 may also be regulated to secure the most effective driving 45 engagement by raising or lowering the stud 20 in the adjusting slot 29 provided in the arm 19. The stud may be firmly clamped in its adjusted position by means of the nut 30.

To provide ample clearance for the belt 50 15, the plate 10 and the cutting blade are preferably disposed slightly to one side of the armature shaft, as shown more clearly in Fig. 2. In order that the grinding wheel 21, carried by the arm or lever 19, may operate uniformly on both sides of the cutting blade, however, the boss or hub 4 is preferably disposed eccentric relative to the armature shaft in such wise that the axis of rotation of said lever 19 will lie in substantially 55 the same plane with the cutting blade. This is also shown more clearly in Fig. 2 of the drawings. In view of this latter construction and relative arrangement of parts, it will be apparent that the distance between 60 the driven pulley 22 and the driving pulley 65

6 on the armature shaft varies, said distance being greater when the arm is swung to the right hand dotted line position of Fig. 2 than when said arm is swung to the other dotted line position shown in Fig. 2. 70 Hence, in the provision of the elastic belt 23, another purpose will be apparent, namely, that of maintaining an effective driving engagement between the armature shaft and the grinding wheel stud regardless of which 75 side of the blade the wheel is operated.

The plate 10 is preferably notched out, as shown at 31, to expose the edge of the cutting blade to the cloth, several thicknesses of which may readily be cut at one time. 80 The plate 11 is thin and smooth, whereby the cloth may slide freely over it, and the entire structure may be readily turned by the handle 2 and pushed along the table or other support to permit the cutter to follow a very 85 irregular line if necessary.

It is obvious that the construction illustrated and described is susceptible of various changes and modifications, and, accordingly, it is not desired to restrict the invention to 90 the embodiment shown, except where limitations appear in the appended claims.

What I claim is:

1. A cloth cutter comprising an electric motor, a rotary cutting blade mounted on an 95 axis at right angles to the axis of the motor, a driving belt for driving said blade directly from the motor armature shaft, a pivotally mounted supporting arm, a grinding wheel mounted on said arm to rotate in a plane 100 at right angles to said blade, and means for driving said grinding wheel from said armature shaft.

2. In a device of the class described, a rotary cutting blade, an electric motor for 105 driving the same, a grinding wheel also driven by said electric motor, said grinding wheel being mounted to rotate in a plane at right angles to the plane of said blade, and means for moving said grinding wheel into 110 engagement with either side of said blade at its edge.

3. In a device of the class described, an extended supporting base, a vertical supporting plate thereon, a rotary blade mounted 115 on said plate, the latter conforming in part to the shape of said blade and being bent over the edge thereof to form a guard, a motor supported by said vertical plate, means for driving said blade from said motor, a grinding wheel mounted to rotate at right angles to the rotation of said blade, and means for driving said grinding wheel.

4. In a device of the class described, an electric motor having a handle at one end 125 and a hub at the other end, an armature shaft projecting from said hub, a pulley on said armature shaft, an arm pivoted to said hub, a grinding wheel supported on said arm, a belt for driving said wheel from said 130

5 pulley, a supporting element for said motor, a base for said supporting element, a rotary cutter carried by said supporting element and projecting into an opening in said 5 base, and means for driving said rotary cutter directly from said armature shaft.

10 5. In a device of the class described, a cutting element, an electric motor for driving the same, said motor being provided with a hub through which the armature shaft of said motor projects, an oscillatory arm mounted on said hub, a stud carried thereby, a pulley and a grinding wheel on said stud, a pulley on the projecting end of said armature shaft, and an elastic driving belt 15 passing over said pulleys whereby said grinding wheel may be rotated when the armature shaft is rotated and whereby said elastic belt may be stretched over said hub 20 to prevent rotation of said grinding wheel when said armature shaft is rotated.

25 6. A cloth cutter comprising an electric motor, a rotary blade adapted to be driven thereby, a supporting arm pivotally mounted about the armature shaft of said motor, a grinding wheel mounted on said arm to rotate in a plane at right angles to said blade, and means for driving said grinding wheel from said armature shaft.

30 7. A cloth cutter comprising an electric motor, a driving shaft projecting therefrom, a cutting blade mounted below said driving shaft on an axis disposed at right angles thereto, a grinding wheel normally positioned above said driving shaft on an axis parallel thereto, and means whereby said grinding wheel may be rocked into engagement with either side of said cutting blade.

35 8. A cloth cutter comprising an electric motor having a casing, a rotary blade carried by said casing, said rotary blade being mounted on an axis at right angles to the axis of the motor, and a belt for driving said blade directly from the motor armature shaft, said motor being movable relatively to said blade whereby the tension of said belt may be adjusted.

40 9. A cloth cutter comprising a base member having an upstanding plate thereon, a rearwardly extending arm on said plate, a motor pivotally mounted thereon, a cutting blade and a pulley carried by said plate, means whereby said pulley and blade may be driven from the armature shaft of said 45 motor, and means whereby said motor may be rocked about its pivot to effect an adjustment of said driving means.

45 10. In a device of the class described, a base member, an upstanding plate thereon, an arm extending rearwardly from said plate, a motor pivotally supported thereon with its armature shaft projecting over said plate, a cutting blade carried by said plate, a pulley associated therewith, a belt for driving said pulley from said armature shaft,

and means for raising or lowering said armature shaft relatively to said pulley to regulate the tension of said belt.

11. In a device of the class described, a base member, an upstanding plate thereon, an arm extending rearwardly from said plate, a motor supported thereon having a hub, the armature shaft of said motor being projected eccentrically through said hub and over said plate, a cutting blade carried by said plate, a pulley associated therewith, means for driving said pulley from said armature shaft, said plate and blade being mounted to one side of said armature shaft and being disposed in the approximate plane of the longitudinal axis of said hub to provide a clearance for said driving means, an arm, a grinding wheel carried thereby, said arm being pivotally mounted on said hub whereby said wheel may be moved into engagement with either side of said blade at its edge, and means for driving said wheel from the motor armature shaft on either side of said blade.

12. A cloth cutter comprising an electric motor, a cutting blade adapted to be driven thereby, a hub on said motor, a grinding wheel, a supporting arm for said wheel rotatably mounted on said hub whereby said wheel may be moved into engagement with either side of said blade, and means for maintaining said arm in operative position on said hub.

13. A cloth cutter comprising an electric motor, a cutting blade adapted to be driven thereby, a hub on said motor, a grinding wheel, a supporting arm for said wheel rotatably mounted on said hub whereby said wheel may be moved into engagement with either side of said blade, and spring means for maintaining said arm in operative position on said hub.

14. A cloth cutter comprising an electric motor, a cutting blade adapted to be driven thereby, a hub on said motor, a grinding wheel, a supporting arm for said wheel rotatably mounted on said hub whereby said wheel may be moved into engagement with either side of said blade, an annular groove in said hub, and spring means carried by said arm adapted to seat in said groove to thereby guide said arm in its movements about said hub.

15. A cloth cutter comprising an electric motor, a cutting blade adapted to be driven thereby, a hub on said motor, a grinding wheel, a supporting arm for said wheel rotatably mounted on said hub whereby said wheel may be moved into engagement with either side of said blade, and means for positively maintaining said arm in upright position when not in use.

16. In a device of the class described, a base member, an upstanding plate thereon, an arm extending rearwardly from said

plate, a motor supported thereon having a hub, the armature shaft of said motor projecting through said hub and over said plate, a cutting blade carried by said plate, 5 means for driving said blade from said armature shaft, an arm, a grinding wheel carried thereby, said arm being pivotally mounted on said hub in such wise that said grinding wheel may be moved into engage-

ment with either side of said blade at its 10 edge, and means for driving said wheel from the motor armature shaft on either side of said blade.

In testimony whereof, I have subscribed my name.

CHESTER H. BEACH.
